DESIGN FOR A SHIRT

Charles Podsen, Brooklyn, N. Y.

Application February 3, 1938, Serial No. 74,829

Term of patent 3½ years

To all whom it may concern:

Be it known that I, Charles Podsen, a citizen of the United States, residing in the Borough of Brooklyn, county of Kings, city and State of New York, have invented a new, original, and ornamental Design for a Shirt, of which the following is a specification, reference being had to the accompanying drawing, forming a part thereof; in which the figure is a front elevation of a shirt showing my design.

The back of the shirt is plain.

The design comprises a shirt having a buttoned-over portion extending in a straight line parallel to and to the side of the vertical center of the shirt front, a button between the diverging points of the rolled-over collar and above the upper edge of the buttoned-over portion, and a breast pocket in combination with a relatively narrow strip, said strip extending obliquely downward from the top of the pocket to adjacent the center button of the buttoned-over portion, as shown.

I claim:

The ornamental design for a shirt, as shown and described.

CHARLES PODSEN.
